MOTORCYCLE ACCESSORY HOUSING

David J. Fritts and Faye B. Fritts, both of 3422 Caracas
Drive, Mesquite, Tex. 75149

Filed Oct. 3, 1974, Ser. No. 511,583

Term of patent 14 years

Int. Cl. D12—11

U.S. Cl. D12—114

FIG. 1

FIG. 2

FIG. 3

FIG. 4

FIG. 6

FIG. 5

FIG. 7

FIG. 1 is a perspective view of a motorcycle accessory housing showing our new design;

FIG. 2 is a front elevational view thereof to a reduced scale;

FIG. 3 is a rear elevational view thereof to a reduced scale;

FIG. 4 is a top plan view thereof to a reduced scale;

FIG. 5 is a side elevational view thereof to a reduced scale;

FIG. 6 is a bottom plan view thereof to a reduced scale; and

FIG. 7 is a perspective view thereof to a greatly reduced scale mounted on a motorcycle with tape deck, twin speakers and top rail installed, all of which have been shown in broken lines for illustrative purposes only.

We claim:

The ornamental design for a motorcycle accessory housing, substantially as shown and described.
